U. JOHNSON

COMPASSES

Filed Dec. 21, 1921

Patented July 17, 1923.

UNITED STATES PATENT OFFICE.

UNO JOHNSON, OF BROOKLYN, NEW YORK.

COMPASSES.

Application filed December 21, 1921. Serial No. 523,969.

To all whom it may concern:

Be it known that I, UNO JOHNSON, a citizen of the Republic of Finland, and resident of the city of New York, borough of Brooklyn, county of Kings, and State of New York, have invented a new and Improved Compass, of which the following is a full, clear, and exact description.

My invention relates to a measuring instrument in the nature of a compass, and more particularly such a compass as is used for proportional division work.

It is an object of my invention to provide an instrument of the nature specified, which may be used for ordinary work in the usual manner, but which will embody a construction permitting of work or drawings being readily divided into desired proportion.

A further object of my invention is the construction of a compass by means of which an operator may readily duplicate a piece of work from one standard scale to another standard scale.

A still further object of this invention is the construction of a measuring instrument of the class specified, the parts of which will be relatively few and efficient in cooperation, and

Still further objects of this invention will appear in the annexed specification taken in connection with the drawings which latter present one practical embodiment of the same, and in which:

Figure 1 is a side elevation of a compass embodying my improved construction.

Figure 2 is a sectional view taken through one of the legs of the compass.

Figure 3 is a fragmentary sectional view taken along the line 3—3 and in the direction of the arrows indicated in Figure 2.

Figure 3^a is an enlarged fragmentary sectional view of a detail of construction.

Figure 4 is a fragmentary enlarged sectional view of a detail of construction.

Figures 5 and 6 are transverse sectional views taken along the line 5—5 and 6—6 and in the direction of the arrows indicated in Figure 1, and

Figure 7 is a sectional view of an optional type of construction which may be resorted to.

It will be seen in these views that the reference numeral 10 indicates one of the legs and 11 the head of the compass, both of these elements being of any desirable shape, and construction, it being further seen that a

second leg is provided which leg is movably connected adjacent its upper end to the head, its body being preferably associated with the first named leg by a screw threaded shaft 12, one end of which is secured to the last named leg in a manner hereinafter described, the body of this shaft being engaged by a knurled nut 13 carried by a swinging block 14 associated with the leg.

It will be noted, referring to the last named leg that the same presents a hollow body 15 in which a longitudinal slot 16 is provided, a scale 17 being positioned adjacent the slot and preferably forming a part of the body 15. Also as has been shown in Figures 1, 5 and 6, a member 18 presenting a scale 19 may be positioned adjacent the slot and upon the side opposite from which the scale 17 extends, it being noted in this connection that the member 18 is detachable from the body 15, this member being preferably held in the position specified by means of screws 20.

As has been best illustrated in Figure 2 an endless band 21 is disposed within the hollow body 15 and retained in proper position therein by passing over rollers 22 arranged adjacent the upper and lower ends of the body aforementioned. This band is preferably formed with a series of openings 23, and carries a pointer 24 which latter extends through and beyond the slot 16 and aligns with the indicating marks of the scales 17 and 19.

Now with a view of moving the band 21 and the pointer 24 it will be noted that I provide a universal connection 25 adjacent the end of the shaft 12 which extends into the hollow body 15, and associated with this connection is a gear 26 which is thus permitted to lock with respect to the shaft, although turning with the same. This gear meshes with openings 23 of the band 21, as has been shown in Figures 2, 3 and 5, and thus upon the shaft 12 being turned by means of its head 27 it will be obvious that the gear 26 will also be turned and that the band 21 and pointer 24 will be correspondingly moved.

Thus in use, assuming that the scale 19 reads for centimeters, and the scale 17 for inches, and that it is desired to scale a centimeter drawing up to inches, the operator will determine the distance between two points by means of my improved instrument, and will then read that portion of the

centimeter scale with which the pointer 24 aligns. By simply turning the shaft 12 until the pointer 24 aligns with a corresponding portion of the scale 17 it will be obvious that an operator will be able to duplicate step-by-step a drawing or piece of work and at the same time be assured that the ratio will be obviously correct.

It will further be understood that by virtue 10 of the universal mounting of the gear 26 that the same will mesh perfectly with the openings 23 of the band 21 as has been indicated in dotted lines in Figure 3, regardless 15 of the angle at which the shaft 12 is disposed with respect to the second leg. Also it will be noted that due to the preferably detachable qualities of the scale 19 that the latter may be supplanted for any desirable 20 scale thus permitting of a universal adaptability of the invention.

In this connection attention is invited to Figure 3^a which shows a construction which may be resorted to with a view of properly retaining the shaft applied with respect to 25 the second leg of the measuring instrument or compass. It will be seen that in assembling the device I preferably pass the end of the shaft 12 through the opening in the body 15 of this leg, subsequent to which I 30 may associate a snap washer or ring 28 with a groove formed adjacent the end of the shaft thus obviously preventing the same from working clear of the leg, it being also seen, as has been shown in Figure 5, that a 35 collar 29 may form an integral part of the body 15, and extend inwardly from the outer face thereof so that the end of the shaft is circumscribed thereby, the outer edge of this collar bearing against the face of the 40 gear 26 to prevent the latter element from working off the shaft.

Finally it will be appreciated, where it is not necessary to provide extremely accurate 45 measurements that the same result accomplished by means of the construction aforementioned may be derived by the use of the structure shown in Figure 7.

In this view it will be noted that as in the 50 previous construction I have provided a leg presenting a hollow body portion 15, and also mounting supporting members 22. However, these supporting members carry a wire 30 instead of a band 21 and in lieu of 55 supporting the gear wheel with the shaft 12, a frame 31 is carried thereby around which the wire 30 is passed.

It will be obvious that by associating an 60 indicating member 32 with the wire 30 that upon the shaft 12 being turned the frame 31 will cause a moving of the wire incident to the latter being coiled around the same, and thus the indicator 32 will be moved to effect 65 the result desired, which result will be accurate enough for ordinary work.

Thus it will be understood that all of the

objects set forth in the preamble of this specification have been accomplished and it will readily be appreciated that numerous modifications of structure might readily be resorted to without in the least departing 70 from the scope of my claims; which are:

1. A compass including a plurality of legs movable with respect to each other, one of said legs being hollow, a scale associated with said leg, and means associated with 75 said hollow leg and actuated upon said legs being moved with respect to each other for registering the movement of one of said legs with respect to the second of the same.

2. A compass including a pair of legs, one 80 of said legs presenting a hollow body, a scale associated with said body, means for moving one of said legs with respect to the second of the same, a pointer movably associated with said scale, and means for connecting said pointer to said leg moving means.

3. A compass including a pair of legs, a screw threaded shaft rotatably attached to one of said legs, a scale associated with the 90 second of said legs, a pointer movable with respect to said scale and positioned adjacent the same, and means for connecting said pointer to said shaft.

4. A compass including a pair of legs, a screw threaded shaft rotatably attached to one of said legs, a scale associated with the second of said legs, a pointer movable with respect to said scale and positioned adjacent the same, a gear secured to the end of said 100 shaft, and means for connecting said gear with said pointer.

5. A compass including a pair of legs, a screw threaded shaft rotatably attached to one of said legs, a scale associated with the 105 second of said legs, a pointer movable with respect to said scale and positioned adjacent the same, a gear secured to the opposite end of said shaft, a member formed with a series of openings capable of engaging with 110 the teeth of said gear, said pointer being secured to said member.

6. A compass including a pair of legs, a screw threaded shaft rotatably attached to one of said legs, a scale associated with the 115 second of said legs, a pointer movable with respect to said scale and positioned adjacent the same, a gear secured to the opposite end of said shaft, a member formed with a series of openings capable of engaging with the 120 teeth of said gear, an endless band secured to said pointer, a gear secured to the end of said shaft, said gear being adapted to mesh with openings in said band.

7. A compass including a pair of legs, a 125 screw threaded shaft rotatably attached to one of said legs, a scale associated with the second of said legs, a pointer movable with respect to said scale and positioned adjacent the same, a gear secured to the opposite end 130

of said shaft, a member formed with a series of openings capable of engaging with the teeth of said gear, an endless band secured to said pointer, a gear secured to the end of 5 said shaft and rockably secured thereto, said gear being adapted to mesh with openings in said band.

8. A compass including a pair of legs, one of said legs presenting a hollow body, an 10 endless band disposed within said body, a pointer carried by said band, a gear adapted to mesh with openings formed in said band, a scale associated with said leg and lying adjacent the path of travel of said pointer, a 15 shaft having one of its ends attached to said gear, said shaft being connected to the first named leg of said compass.

9. A compass including a pair of legs, one of said legs presenting a hollow body, an

endless band disposed within said body, a 20 pointer carried by said band and extending through and beyond a slot formed in said body, a gear adapted to mesh with openings formed in said band, a scale associated with said leg and lying adjacent the path of 25 travel of said pointer, a shaft having one of its ends attached to said gear, said shaft being connected to the first named leg of said members.

10. A compass including a pair of legs, 30 a scale carrying member detachably and directly secured to one of said legs, a pointer adapted to coact with said scale, and means for moving one of said legs with respect to the other, said means being connected to said 35 pointer whereby to move the latter in proportion to the movement of said legs.

UNO JOHNSON.
